UNITED STATES PATENT OFFICE.

NICHOLAS MARCALUS, OF PLAINFIELD, NEW JERSEY, ASSIGNOR TO NILES-BEMENT-POND COMPANY, OF NEW YORK, N. Y., A CORPORATION OF NEW JERSEY.

FROG AND SWITCH PLANER.

Application filed June 20, 1924. Serial No. 721,229.

This invention relates to planers and like machines and more particularly to the operating and controlling mechanism for the tools and tool holders thereof. The planer 5 illustrated in the accompanying drawings is constructed particularly for the planing of frogs and switches of railway rails and is similar to that shown in a copending application, Serial No. 675,203, filed November 10, 1923. Such work requires very heavy cutting operations and the machine must of course be constructed accordingly. Furthermore, these heavy cuts subject the tools to extremely heavy strains and vibrations and 15 make the rigid supporting of the tools essential.

One of the objects of my invention is to provide an improved tool feeding mechanism for planers and like machines, such 20 mechanism preferably including an electric feed motor and automatic controlling means therefor.

Another object of my invention is to provide improved clamping means for the tool 25 supporting members, such clamping means preferably being operated from the feed motor and being adapted through a simple and novel mechanism to automatically release the tool supporting members prior to 30 each feeding operation and clamp the same after each feeding operation.

Another object of my invention is to provide means in connection with the above described feeding and clamping means for 35 positively pivoting the tool holder outwardly at the end of each cutting operation whereby marring of the work by the tool during the return or noncutting stroke of the work table is prevented.

With the above and other objects in view, 40 my invention consists in the features of construction and operation set forth in the following specification and illustrated in the accompanying drawings. In such drawings 45 annexed hereto and forming a part of this specification, I have shown certain embodiments of my invention in a planer but it will be understood that the invention can be otherwise embodied and that the drawings 50 are not to be construed as defining or limiting the scope of the invention, the claims appended to this specification being relied upon for that purpose.

Referring to the figures of the drawings:

Fig. 2 is a fragmentary plan view thereof, partially in section.

Fig. 3 is a front elevation of Fig. 2, partially in section. 60

Fig. 4 is an enlarged sectional view taken on line 4-4 of Fig. 2.

Fig. 5 is a fragmentary detail view partially in section on line 5-5 of Fig. 4.

Fig. 5^a is a perspective view of a detail.

Fig. 6 is a front end elevation of the cross rail.

Fig. 7 is a view like Fig. 6 but showing portions thereof broken away.

Fig. 8 is a sectional view taken on line 70 8-8 of Fig. 6.

Fig. 9 is a detail view showing the tool holder clamping shafts.

Fig. 10 is an enlarged detail sectional view 75 of the tool slide clamping mechanism taken on line 10-10 of Fig. 2.

Fig. 11 is a view thereof taken on line 11 of Fig. 2.

Fig. 12 is a detail view of the saddle clamping mechanism taken on line 12-12 80 of Fig. 13.

Fig. 13 is a view thereof taken on line 13-13 of Fig. 2.

Fig. 14 is a view thereof taken on line 85 14-14 of Fig. 6.

Fig. 15 is an enlarged detail view of the feed controlling mechanism, such view being taken approximately on line 15-15 of Fig. 8.

Fig. 16 is a detail view of the feed pinion 90 shifting mechanism.

Fig. 17 is a sectional view thereof on line 17-17 of Fig. 16.

Fig. 18 is a sectional view illustrating the mechanism for operating the feed-motor controller. 95

Fig. 19 is a plan view of the mechanism shown in Fig. 18.

In the drawings, 1 indicates the bed of a planer having a work table 2 slidably mounted thereon and a pair of uprights 3 respectively at opposite sides of the table. As illustrated, these uprights are made very heavy to withstand the severe cutting operations to be performed by this machine. A 100 cross rail 4 is mounted to slide vertically on the uprights and is adapted to slidably support a pair of tool head saddles 5 and 5' 105

- thereon. Bolts 6 threaded into the rail are adapted to clamp the rail to the uprights. Tool slides 7 and 7' are mounted for vertical movement in the saddles 5 and 5' in the usual manner. Swivelly mounted on a center pin 8 on each tool slide is a block 9 and a tool holder 10 pivoted to the block at 11 is adapted to support a pair of tools 12 and 12' therein.
10. The upper arcuate portion of each block 9 is provided with teeth 13 engaged by a worm 14. Rotation of the worm 14 is adapted to angularly adjust each block about its pivot 8. An eccentric bolt 15 rotatably mounted in a 15 forwardly extending portion 16 of each slide and provided with an operating handle 17 thereon is adapted to securely clamp each block in its adjusted position. In the drawings, the handles are shown in the block 20 clamping position. The blocks can be unclamped by moving the handles outwardly. Other means are provided at 18 for securing the tools 12 and 12' in each tool holder 10.
- A toothed plate 19 is bolted to the tool 25 holder above each tool 12 and 12'. These plates are slotted to permit the plates to be vertically adjusted to engage the upper ends of the tools and, when clamped in such position by bolts 20, the plates take the upward 30 thrust of the tools in a very rigid manner.
- For the purpose of securing rigidity, the uprights 3 are preferably constructed and connected together in the manner shown in Fig. 2. The cross rail engaging portions 35 of the two uprights are made very wide whereby such portions project inwardly to approach each other very closely at 21, these portions being secured together by bolts at 22. The forward faces of these portions 40 are finished off at 23 to receive the rail. The rail has a rearwardly extending portion 24 extending between the uprights. A clamping plate 25 and bolts 26 are provided on this portion for securing the rail to the 45 uprights. This construction provides a rigid backing extending substantially along the entire operating portion of the rail. A similar construction is disclosed and claimed in Patent No. 1,519,332 dated December 16, 50 1924.
- The table 2 is adapted to be reciprocated from a main motor (not illustrated). A motor 27 is mounted on a rearwardly extending bracket 28 on the cross rail and, as 55 illustrated in the drawings, this motor is adapted to feed and traverse the tool supports and to move the cross rail on the uprights. The main motor and the motor 27 are automatically controlled by a pilot 60 switch 29 operated by table dogs 30 engaging a switch arm 31. This mechanism and its operation are more fully disclosed in Patent No. 1,299,192. The specific tool feeding and traversing mechanism illustrated in
- the drawings and operated from the motor 65 27 is hereinafter described.
- A pair of screws 32, 32' are non-rotatably supported in the uprights 3 and the cross rail is supported on a pair of nuts 33, 33' threaded to these screws. A shaft 34 70 extending along the rail is provided with worms 35, 35' thereon in mesh with worm gear teeth on these nuts. Rotation of the shaft 34 is adapted to elevate and lower the rail on the uprights. 75
- A pair of screw shafts 36 and 37 rotatably mounted in the cross rail are respectively connected to the saddles 5 and 5' whereby rotation of such screws serves to adjust the saddles along the rail in the usual manner. 80
- A pair of shafts 38 and 39 rotatably mounted in the cross rail are respectively connected to the tool slides 7 and 7'. A spiral gear 40 rotatably mounted in the saddle 5 is splined to the shaft 38. This gear is in 85 mesh with spiral gear teeth on a nut 41 rotatably supported in the saddle 5 and threadedly engaging a non-rotary screw 42 carried by the slide 7. A like connection is provided from the shaft 39 to a screw 42' 90 in the slide 7'. Rotation of the shafts 38 and 39 are therefore respectively adapted to adjust the slides 7 and 7'. 95
- The motor 27 is adapted to operate the shafts 36, 37, 38 and 39 to feed and traverse the saddles 5 and 5' and slides 7 and 7'. This motor is also adapted to operate the shaft 34 to adjust the cross rail on the uprights. This motor is furthermore adapted to automatically operate clamping mechanism for clamping the saddles and slides for each cutting operation and to release the same for each feeding operation. The operative connections from the motor to these mechanisms is hereinafter specifically described. 100
- The driving connections from the motor 27 to the shafts 36, 37, 38 and 39 for automatically feeding the saddles and slides is as follows: The motor shaft 43 is rotatably supported in a housing 44 secured to the front end of the cross rail, this housing preferably being an integral part of the motor supporting bracket 28. A worm 45 splined to this shaft and rotatably supported in a block 46 115 is in mesh with a worm gear 47 loose on a shaft 48. A feed gear 49 is keyed to the hub of the worm gear (Fig. 8) and a second feed gear 50 is also loosely mounted on the shaft 48. A wide pinion 51 in mesh with gear 49 is also in mesh with a wide pinion 52 in mesh with gear 50. Thus when the gear 49 is rotated in one direction by the motor, the gear 50 is rotated therefrom at the same speed in the opposite direction. 120
- A pinion 53 splined to each of shafts 34, 36, 37, 38 and 39 is adapted to be shifted into mesh with either of gears 49 and 50. 125

A shifting device for each of these pinions is provided in the housing 44 as shown in Figs. 16 and 17. This device comprises a handle 54 connected to an element 55 having a shoe thereon loosely seated in an annular groove 56 in the hub of the pinion. A spring pressed detent 57 is adapted to hold the pinion in engagement with either gear or in a neutral position midway between the 10 gears.

The mechanism for automatically controlling the extent of motor rotation in the feeding operation is as follows: Referring particularly to Figs. 7, 8 and 15 of the drawings, the circuit to the motor 27 passes through a switch in a controller box 58. An arm 59 keyed to a shaft 60 has an adjustable element 61 in the free end thereof adapted by movement inwardly of the box to break 15 the motor circuit. The shaft 60 is rotatably and slidably mounted in bearings 62 and 63. An arm 64 on the shaft has a roller 65 at its free end adapted to ride on the outer face of the gear 50 as the latter is rotated. 20 This face of gear 50 is provided therearound with a plurality of series of differently spaced depressions 66.

The upper portion of the shaft 60 is toothed to provide a rack 67 engaged by a 30 pinion 68 loose on the shaft 48. By means of a knob 69 the pinion can be rotated to adjust the shaft 60 longitudinally and bring the roller 65 into line with any one of the 35 said series of depressions 66. A spring 70 normally operates to hold the roller 65 against the said gear face. When the roller comes opposite a depression 66, the roller drops thereinto whereupon the shaft 60 and arm 59 rock sufficiently to break the circuit 40 within the controller box 58. In the drawings, I have illustrated the gear 50 as provided with five series of depressions 66 but it will be understood that any number of 45 series of such depressions can be provided as desired. As shown in Fig. 6, a pointer 71 in connection with five points 72 provides means for indicating the proper rotary adjustment of the knob 69 to bring the roller into line with any one of the five series of 50 depressions.

In the feeding operation the gear 50 is rotated in the direction of the arrow shown in Fig. 7, the gear 49 of course rotating in the opposite direction. The pinions 53 are 55 meshed with one or the other of the gears 49 or 50, depending upon the direction it is desired to feed the saddles and slides controlled thereby. The amount of feeding movement imparted by the motor depends upon the adjusted position of the roller 65. The innermost series of depressions 66 contains five equally spaced depressions and the roller, when opposite this series, therefore permits a feeding movement equal to one-fifth rotation of the gear 50. The outermost

series of depressions 66 contains twenty-eight equally spaced depressions and the roller, when opposite this series, therefore permits a feeding movement equal to one-twenty-eighth rotation of the gear 50. The 70 operation of this mechanism is hereinafter more specifically described.

As has been heretofore stated, my invention also contemplates means operated by the feed motor for automatically clamping 75 the saddles 5 and 5' to the cross rail and the slides 7 and 7' to the saddles after each feeding operation and for releasing such clamping mechanism prior to each feeding operation. This mechanism will now be described.

The saddle 5' (Figs. 3, 12 and 13) is accurately adjusted on the cross rail by means of a taper gib 73'. A saddle clamping element 74' slidably mounted in the saddle rests on this gib. A shaft 75' mounted in the saddle above this element rotatably supports a pair of gears 76' and 77' thereon, the gear 76' being provided with an eccentric hub 78' in engagement with the clamping element 74'. In Figs. 12 and 13, the gear 76' and its eccentric hub 78' are shown in the saddle clamping position. Rotation of the gear 76' 180° will release the saddle clamping pressure on the element 74' and gib 73'. The saddle 5 is provided with a 95 like mechanism indicated in the drawing by like reference characters not primed.

The slides 7 and 7' are provided with similar clamping mechanisms (Figs. 2, 3, 6, 10 and 11). The slide 7 is accurately adjusted in the saddle by means of a taper gib 79. A slide clamping element 80 mounted in the saddle engages at one side against this gib and at its other side against an inclined portion of a vertical rod 81. At its upper end, this rod is provided with a rack in engagement with the before mentioned gear 77. Rotation of the gear in one direction is adapted to move the rod upwardly and clamp the slide in the saddle and rotation of the gear in the opposite direction is adapted to move the rod downwardly and release the clamping mechanism.

In addition to its slide clamping function, the rod 81 also operates to automatically and positively pivot the tool holder 10 outwardly at the end of each cutting operation whereby marring of the work by the tool during the return or non-cutting stroke of the work table is prevented. As shown in Fig. 11, the saddle 5 carries an element 82 therein forwardly of the rod 81. The forward face of this element presents a vertical surface engaging a pin 83 carried by the tool holder 10. The supporting shank of the element 82 is normally spring pressed rearwardly into a recess 84 in the rod 81. The construction is such that when the rod moves downwardly to release the clamp to permit feeding of the side, the shank of the element 82 is

forced out of the recess 84 in a manner to pivot the tool holder outwardly. Conversely, when the rod moves upwardly to clamp the slide for the cutting operation, the recess 84 permits the tool holder to pivot back to its normal cutting position.

The clamping gear 76, 77 and 76', 77' are respectively operated by gears 85 and 86. The gear 86 is splined to a shaft 87 and the gear 85 is splined to a sleeve 88 loose on this shaft, the shaft being rotatably supported in the saddle 5' and the sleeve rotatably supported in the saddle 5. The gear 86 is so positioned as to be shifted into mesh with either of its cooperating clamping gears 76' and 77'. A lever pivoted on the saddle 5' at 89' has an arm 90' carrying a yoke 91' straddling this gear 86 and a handle 92' is provided on the lever for shifting this gear along the sleeve into mesh with either of gears 76' and 77'. A gear shifting mechanism including a handle 92 is provided on the saddle 5 for shifting the gear 85 into mesh with either of gears 76 and 77.

25 The clamping shaft 87 and sleeve 88 are adapted to be automatically operated from the worm supporting block 46 through the following mechanism: The block is mounted for free sliding movement axially of the worm 45. A pair of racks 93 and 94 on the block are respectively in mesh with a pair of gears 95 and 96 respectively keyed to the shaft 87 and sleeve 88 (Fig. 5). The racks are connected to the block by means of an element 97 shown in Fig. 5a. A central stud 98 on this element engages within a cooperating circular recess in the top of the block. A pair of lugs 99 and 100 on the top of the element respectively engage within cooperating recesses in the bottoms of the racks 93 and 94. The construction is such that as the block is moved longitudinally, the racks are moved with balanced forces therewith. It will be seen that since the element 97 is free to rotate about its central stud 98, the two racks will be operated with balanced forces in a manner to effect equal clamping of the saddles and slides. A spring pressed plunger 101 and a ball bearing 102 are provided at the forward end of the block for taking the thrust thereof during the unclamping and feeding operations as hereinafter described.

55 During the unclamping and feeding operations, the motor is rotated in a direction to rotate the gear 50 in the direction indicated by the arrow in Fig. 7. During the clamping operation, the motor is rotated in the opposite direction, these rotations being automatically controlled by the pilot switch 29 in timed relation to the table reciprocatation. A pair of pawls 103 of slightly different lengths engage the gear 50 and normally permit rotation of the gears 49 and 50 in the unclamping and feeding direc-

tion but prevent rotation thereof in the opposite direction. A pawl 104 engages the gear 49 and normally prevents rotation of the gears 49 and 50 in the unclamping and feeding direction. In Fig. 7, the parts are 70 shown in the unclamping and feeding position, the pawl 104 being held up in the disengaged position by a pin 110 on the block 46.

The motor 27 can be continuously operated for traversing the rail saddles and slides by the following mechanism. A control box 105 mounted on the bottom of the housing 44 has two spring pressed contacts 106 and 107 extending outwardly therefrom. 75 A handle 108 pivoted to the housing has portions thereof extending over the contacts 106 and 107 whereby movement of the handle in one direction engages one contact to rotate the motor in one direction and movement 80 thereof in the opposite direction engages the other contact to rotate the motor in the opposite direction.

When operating the motor in the direction indicated by the arrow in Fig. 7 (upward 90 movement of the handle 108), the saddles and slides are unclamped and the pawl 104 is held in the disengaged position by the pin 110 as shown in Fig. 7. The parts are therefore free to be continuously rotated in 95 this direction. When operating the motor in the opposite direction however (downward movement of the handle 108), the worm rotation would normally move the block 46 backwardly in a manner to clamp 100 the saddles and slides and furthermore the pawls 103 engage the gear 50 and normally prevent rotation of the motor in this direction. It is therefore obvious that the motor cannot be rotated in this direction for traversing without first disengaging the pawls 103 and holding the block 46 from movement backwardly to the saddle and slide clamping position. The following described mechanism is provided for 105 overcoming this objection.

A rod 109 extending upwardly through the housing 44 has its upper end U-shaped over the block 46, the short leg of the rod having a pin 110' therein above a tail on the 115 pawls 103. Downward movement of the handle 108 is adapted to force the rod 109 downward and, through pin 110', to disengage the pawls 103 and to engage the U portion of the rod within a recess 111 in the 120 block whereby rearward movement of the block is prevented. In such position of the parts, the mechanism is free to be continuously operated in the direction opposite to that shown by the arrow in Fig. 7. A spring 125 112 surrounding the rod 109 normally holds this rod in its uppermost position so that when the handle 108 is elevated the rod 109 is allowed to rise.

Referring to Figs. 18 and 19, a controller 130

120 is provided for governing the operation of the feed motor 27. The controller 120 in many respects operates in the manner of the limit switch which is provided in many planer control systems. However, as above set forth, the feeding movement of the motor 27 is not limited by means of a controller. The controller 120 is operated by the block 46 in order to permit the reversing of the feed motor 27 by means of the pilot switch 29. A complete description of the operation of the feed-motor controller and the control circuits for operating the planer disclosed in this application is set forth in the application of R. C. Deale et al, Serial No. 726,345, filed July 16, 1924.

The housing or support 44 carries a bracket 121 which directly supports the controller 120. The shaft 122 of the controller 20 is pinned in any suitable manner to a stud bolt 123 which projects through the bracket 121. The bolt 123 carries a collar 124 which has two arms 125 and 126 projecting from it. The arm 125 carries two rollers 127 and 128 and the arm 126 carries a single roller 129. The rollers 129 and 127 are adapted to engage cam surfaces 130 and 131 on a cam member 132. The cam member 132 is secured to the block 46 and accordingly is operated in accordance with the clamping and unclamping movements effected by the block. The roller 128 is adapted to engage the wedge-shaped end of a plunger 133. A spring member 134 exerts a force to maintain the plunger 133 in engagement with the roller 128.

Assuming the block 46 to be moved towards the right, as shown in Figs. 18 and 19 of the drawings, to effect a clamping operation, the cam surface 131 of the cam member 132 will engage the roller 127 and force the plunger 133 towards the right against the action of the spring member 134. When the collar 124, which carries the roller 127, 45 is rotated through a limited angle, the spring 134 acting on the plunger 133 will move the roller 127 out of engagement with the cam surface 131 and move the roller 129 into engagement with the cam surface 130. The feed-motor controller 120 is now in position 50 for operating the feed motor to effect an unclamping operation and a feeding movement when the pilot switch 29 is operated at the end of the cutting stroke of the planer. When the feed motor 27 is operated in a reverse direction at the end of the cutting stroke, the block 46 is moved towards the left, as shown in Figs. 18 and 19 of the drawings. Such movement of the block 55 causes the cam surface 130 of the cam member 132 to rotate the drum controller 120 by means of the roller 129. When the collar 124 is rotated through a predetermined distance, the plunger 133 is operated by the spring 60 134 to move the collar to the position shown

in Fig. 19 of the drawings. The controller 120 opens the feed motor circuit and establishes a dynamic braking circuit through the feed motor after a predetermined feeding movement at the end of the cutting stroke. 70 The controller opens the feed motor circuit and permits such motor to effect a drifting stop when a clamping operation is being effected at the end of the return stroke.

The general operation of the machine is 75 as follows: Before beginning the cutting operation, the pinions 53 of the tool holders it is desired to feed are engaged with one or the other of the gears 49 and 50, depending upon the direction it is desired to feed. The 80 construction is such that the handles 54 for the saddle screws 36 and 37 should be pointed in the direction it is desired to feed the saddles. For example, as shown in Fig. 3, the handle 54 for the screw 37 pointing to 85 the left, is adapted to feed the saddle 5' to the left. Also the knob 69 should be adjusted to provide the desired amount of feeding movement. Furthermore the gears 85 and 86 should each be shifted into engagement with one of gears 76, 77 and 76' and 77', depending upon whether it is desired to clamp the saddles or slides. These 90 adjustments having been properly made and the tools properly set in position, the operation is as follows:

As shown in Fig. 7, the unclamping and feeding movements have just been completed and the feeding mechanism is at rest. The work table 2 however is continuing its backward stroke in the non-cutting direction. Engagement of the right hand dog 30 (Fig. 1) with the arm 31 of the pilot switch 29 reverses the direction of the main motor and table reciprocation and energizes the 100 feed motor 27 to rotate the gear 50 in a direction opposite to the arrow shown in Fig. 7. Rotation of the gears 49 and 50 in this direction however is prevented by the pawls 105 103. The worm gear 47 being thus held 110 against rotation, the rotation of the worm 45 will operate to move the block 46 backwardly (Fig. 4). This operation rotates the shaft 87 and sleeve 88 anti-clockwise and clamps the saddles or slides through the 115 mechanism heretofore described. The clamping operation will stall the motor 27 before the rear end of the block 46 engages the housing 44. With the tools thus clamped, the table continues its stroke in the cutting 120 direction.

When the left hand dog 30 (Fig. 1) hits the pilot switch arm 31, the direction of the main motor and table is reversed and the motor 27 is energized to rotate the gear 50 125 in the direction of the arrow (Fig. 7). The pawl 104 however prevents rotation of the gears 49 and 50 in this direction. The worm gear 47 being thus held against rotation, the rotation of the worm 45 will operate to 130

move the block 46 forwardly. This operation rotates the shaft 87 and sleeve 88 clockwise (Fig. 4) and unclamps the saddles and slides. This forward unclamping movement 5 operates through the pin 110 on the block 46 to raise the pawl 104 to permit rotation of the gears 49 and 50 in the feeding direction.

The saddles and slides now being unclamped and the pawl 104 being raised, the gear 50 rotates in the direction of the arrow (Fig. 7). This rotation continues until the roller 65 drops into the next depression 66. The spring 70 thereupon moves the arm 59 and element 61 sufficiently to break the holding circuit of a switch which controls the motor 27. The circuit for performing this operation passes through the control box 58. The main circuit of the motor 27 is thereupon broken and the motor stopped. It should be understood however that the coasting inertia of the gear 50 is sufficient to raise the roller 65 out of the depression 66 preparatory to the next feeding operation 25 before the gear stops. The tool holders have now been fed the desired amount, the feed mechanism is at rest, the table is continuing its movement in the non-cutting direction, and the various parts of the machine continue on again through the cycle of operations above described. The electrical connections for automatically controlling the feed motor, which do not comprise a part of my present invention, are more fully illustrated and described in copending application of R. C. Deale et al., Serial No. 726,346, filed July 16, 1924, referred to above.

What I claim is:

1. A tool feeding mechanism for planers 40 or the like comprising in combination, a tool support, a pair of feed gears, means for optionally connecting the tool support to the feed gears, power means automatically operative to intermittently and simultaneously 45 rotate the feed gears a predetermined amount in relatively opposite directions, and rotary means mounted coaxially of the feed gears for varying the amount of gear rotation.

2. A tool feeding mechanism for planers 50 or the like comprising in combination, a tool support, a pair of feed gears, means for optionally connecting the tool support to the feed gears, a motor for simultaneously rotating the feed gears in relatively opposite 55 directions, and means for stopping the motor after a predetermined rotation of the said gears, the last said means being adjustable whereby to vary the amount of gear rotation.

3. A tool feeding mechanism for planers 60 or the like comprising in combination, a tool support, a pair of feed gears, means for optionally connecting the tool support to the feed gears, a motor for simultaneously rotating the feed gears in relatively opposite

directions, means for stopping the motor after a predetermined rotation of the said gears, the last said means being adjustable whereby to vary the amount of gear rotation, and means whereby the motor can be operated continuously for tool traversing purposes.

4. A tool feeding mechanism for planers or the like comprising in combination, a tool support, a pair of feed gears, means for optionally connecting the tool support to the feed gears, a motor for simultaneously rotating the feed gears in relatively opposite directions, and means controlled by one of the feed gears for stopping the motor after a predetermined rotation of the said gears, the last said means being adjustable whereby to vary the amount of gear rotation.

5. A tool feeding mechanism for planers or the like comprising in combination, a tool support, a pair of feed gears, means for optionally connecting the tool support to the feed gears, a motor for simultaneously rotating the feed gears in relatively opposite directions, a switch in the motor circuit, and switch controlling means engaging the face of one of the feed gears, the said face being provided with means for operating the controlling means to open the circuit after a predetermined rotation of the said gears and the controlling means being adjustable over the said face to vary the amount of the rotation.

6. A tool feeding mechanism for planers or the like comprising in combination, a tool support, a pair of feed gears, means for optionally connecting the tool support to the feed gears, a motor for simultaneously rotating the feed gears in relatively opposite directions, a switch in the motor circuit, and switch controlling means engaging the face of one of the feed gears, the said face being provided therearound with a plurality of series of differently spaced depressions for receiving the controlling means, the dropping of the controlling means into one of the depressions being adapted to open the circuit and the controlling means being adjustable over the said face to any of the said series whereby to vary the amount of gear rotation.

7. In a machine tool, the combination of a support, a tool carrying member thereon, means including a power operated worm engaging a worm gear for intermittently feeding the member, clamping means for the member, and means engaging the worm and operatively connected to the clamping means for clamping the member to the support, rotation of the worm in one direction being adapted to release the member and thereafter feed the same and rotation of the worm in the opposite direction being adapted to clamp the member.

8. In a machine tool, the combination of a

- support, a tool carrying member thereon, means including a power operated worm engaging a worm gear for intermittently feeding the member, clamping means for the member, means engaging the worm and operatively connected to the clamping means for clamping the member to the support, rotation of the worm in one direction being adapted to release the member and thereafter feed the same and rotation of the worm in the opposite direction being adapted to clamp the member, and means for continuously rotating the worm gear for tool traversing purposes.
13. In a machine tool, the combination of a support, a tool carrying member thereon, a worm gear for feeding the member, a power operated worm engaging the worm gear, a block rotatably supporting the worm, the block and worm being mounted for sliding movement, clamping means for the member, a pinion connected to the clamping means, a rack connected to the block and engaging the pinion whereby rotation of the worm in one direction moves the block and rack in one direction to clamp the member and rotation of the worm in the opposite direction moves the block and rack in the opposite direction to unclamp the member.
14. In a machine tool, the combination of a support, a tool carrying member thereon, means including a power operated worm engaging a worm gear for intermittently feeding the member, clamping means for the member, means engaging the worm and operatively connected to the clamping means for clamping the member to the support, rotation of the worm in one direction being adapted to release the member and thereafter feed the same and rotation of the worm in the opposite direction being adapted to clamp the member, and means for preventing rotation of the worm gear in the feeding direction until the unclamping operation has been effected.
15. In a machine tool, the combination of a support, a tool carrying member thereon, a worm gear for feeding the member, a power operated worm engaging the worm gear, a block rotatably supporting the worm, the block and worm being mounted for sliding movement, clamping means for the member, and operative connections between the clamping means and the block whereby rotation of the worm in one direction slides the block in one direction to clamp the member and rotation of the worm in the opposite direction slides the block in the opposite direction to unclamp the member.
16. In a machine tool, the combination of a support, a tool carrying member thereon, means including a power operated worm engaging a worm gear for intermittently feeding the member, means operated by axial movement of the worm for clamping the member to the support, rotation of the worm in one direction being adapted to release the member and thereafter feed the same and rotation of the worm in the opposite direction being adapted to clamp the member, a pawl for preventing rotation of the worm gear in the feeding direction until the unclamping operation has been effected, and means adapted to release the pawl upon axial movement of the worm in the unclamping direction.
17. In a machine tool, the combination of a support, a tool carrying member thereon, means including a power operated worm engaging a worm gear for intermittently feeding the member, means operated by axial movement of the worm for clamping the member to the support, rotation of the worm in one direction being adapted to release the member and thereafter feed the same and rotation of the worm in the opposite direction being adapted to clamp the member, and means for preventing rotation of the worm gear in the non-feeding

direction whereby the worm upon rotation in the non-feeding direction moves axially to clamp the member.

17. In a machine tool, the combination of 5 a support, a tool carrying member thereon, means including a power operated worm engaging a worm gear for intermittently feeding the member, means operated by axial movement of the worm for clamping 10 the member to the support, rotation of the worm in one direction being adapted to release the member and thereafter feed the same and rotation of the worm in the opposite direction being adapted to clamp the member, means for preventing rotation of 15 the worm gear in the non-feeding direction whereby the worm upon rotation in the non-feeding direction moves axially to clamp the member, means for continuously rotat- 20 ing the worm and worm gear for tool traversing purposes, and means for rendering the third mentioned means ineffective during the traversing operation in one direction.
18. In a machine tool, the combination of 25 a plurality of tool supports, means adjustably supporting the tool supports, means including a power operated worm engaging a worm gear for intermittently feeding the supports, and means operated by axial movement of the worm for clamping the supports to the first said means with balanced forces 30 after the feeding operation and for releasing the same therefrom prior to the feeding operation.

19. In a machine tool, the combination of 40 a pair of tool supports, means adjustably supporting the tool supports, clamping means for each tool support, means including a power operated worm engaging a worm gear for intermittently feeding the supports, and means including a shaft for each tool support respectively connecting the clamping means with the worm whereby rotation 45 of the worm in one direction will release the clamping means prior to the feeding operation and rotation thereof in the opposite direction will clamp the tool supports after the feeding operation.

20. In a machine tool, the combination of 50 a pair of tool supports, means adjustably supporting the tool supports, clamping means for each tool support, means including a power operated worm engaging a worm gear for intermittently feeding the supports, a pair of coaxially mounted shafts for actuating the clamping means for said pair of tool supports, and a pair of gears respectively mounted on the shafts and connected to the worm, whereby rotation of the worm in one direction will move said worm axially to rotate said shafts for the clamping means and release the clamping means prior to the feeding operation and rotation thereof in the opposite direction will move said

worm axially in the opposite direction and clamp the tool supports after the feeding operation.

21. In a machine tool, the combination of 70 a cross rail, a saddle slidably mounted thereon, a tool slide in the saddle, means for clamping the saddle to the rail and the slide to the saddle, means including a power operated worm engaging a worm gear for intermittently feeding the saddle and slide, 75 and means operatively connecting the clamping means and worm whereby rotation of the worm in one direction will move said worm axially to release the clamping means prior to the feeding operation and rotation 80 thereof in the opposite direction will move said worm axially in the opposite direction to effect the clamping after the feeding operation.

22. In a machine tool, the combination 85 of a cross rail, a saddle slidably mounted thereon, a tool slide in the saddle, means for clamping the saddle to the rail and the slide to the saddle, means including a power operated worm engaging a worm gear for 90 intermittently feeding the saddle and slide, a clamping shaft on the cross rail operatively connected to the worm, and means for optionally connecting the shaft to either the saddle clamping means or the slide 95 clamping means, the construction being such that rotation of the worm in one direction releases the clamping means prior to the feeding operation and rotation thereof in the opposite direction effects clamping by 100 the clamping means.

23. In a machine tool, the combination of 105 a support, a tool carrying member mounted thereon, power operated means for intermittently feeding the member, a clamping element mounted to slide transversely of the said feeding movement, and means automatically operated in timed relation to the feeding means for transversely moving the said element to clamp the member after 110 each feeding movement and to release the same prior to each feeding movement.

24. In a machine tool, the combination 115 of a support, a tool carrying member mounted thereon, power operated means for intermittently feeding the member, a clamping element movable transversely of the said feeding movement, a rotary cam operative against the said element, and means automatically operative in timed relation to the feeding means for rotating the cam to clamp the member after each feeding movement and to release the same prior to each feeding movement.

25. In a machine tool, the combination of 125 a support, a tool carrying member mounted thereon, means including an electric motor for intermittently feeding the member, a clamping element mounted to slide transversely of the said feeding movement, and 130

means automatically operated by the motor for transversely moving the said element to clamp the member after each feeding operation and to release the same prior to each feeding movement.

26. In a machine tool, the combination of a rail, a saddle slidably mounted thereon, a tool slide in the saddle, power operated means for intermittently feeding the saddle and slide, two clamping means mounted in the saddle and movable transversely of the saddle movement and slide movement respectively, and means automatically operated in timed relation to the feeding means for moving the clamping means to clamp the saddle and slide against movement relative to their supports after each feeding movement and to release the same prior to each feeding movement.

27. In a machine tool, the combination of a rail, a saddle slidably mounted thereon, a tool slide in the saddle, a pair of taper gibbs respectively operative to accurately slidably fit the saddle and slide to their supporting members, clamping means mounted in the saddle adjacent the gibbs, and means for forcing the clamping means against the gibbs to clamp the saddle and slide against movement in their supports.

28. In a machine tool, the combination of a rail, a saddle slidably mounted thereon, a tool slide in the saddle, two clamping

means for respectively clamping the saddle and slide against movement relative to their supports, a pair of gears on the saddle respectively connected to the clamping means, and power operated means for operating the said gears to clamp the saddle and slide against movement in their supports.

29. In a machine tool, the combination of a cross rail, a tool carrying member thereon, a pivoted tool holder carried by the member, means including a power operated worm engaging a worm gear for intermittently feeding the member, and means operated by axial movement of the worm for pivoting the tool holder outwardly prior to each feeding operation.

30. In a machine tool, the combination of a support, a tool carrying member thereon, a pivoted tool holder carried by the member, means including a power operated worm engaging a worm gear for intermittently feeding the member, and means operated by the axial movement of the worm for clamping the member to the support after the feeding operation and for releasing the same therefrom and pivoting the tool holder outwardly prior to the feeding operation.

In testimony whereof, I hereto affix my signature.

NICHOLAS MARCALUS.
